UNITED STATES PATENT OFFICE.

GEORGE McCALL, OF PHILADELPHIA, PENNSYLVANIA.

RAILROAD-SWITCH.

SPECIFICATION forming part of Letters Patent No. 289,677, dated December 4, 1883.

Application filed June 5, 1883. (No model.)

To all whom it may concern:

Be it known that I, GEORGE McCALL, a citizen of the United States, and a resident of the city and county of Philadelphia, and State 5 of Pennsylvania, have invented a new and useful Improvement in Railroad-Switches, of which the following is a specification.

The object of my invention is to furnish a switch combining the advantages of the stub 10 and needle switches, and free from the disadvantages to which both are subject.

In the accompanying drawings, forming part of this specification, and in which similar letters of reference indicate like parts throughout the several views, Figure 1 represents a plan view of my invention, the switch being set for the main line; Fig. 2, a plan view, the switch being set for the siding; Fig. 3, a top view of the plate A, upon which the stub 15 slides; Fig. 4, a side elevation of the same. Fig. 5 represents a sectional view of the plate or switch-chair A on the line x x , Fig. 2, the switch being set for the siding; and Fig. 6, a perspective view of the stub, showing the elevation of the siding-rail.

B is a tongue or grooved rail pivoted in a suitable manner at C. This rail has flaring ends, as shown, so as to insure the catching of the flanges of the wheels when the switch is 20 set for the siding.

D is a movable rail, and forms part of the main track, and is connected with the tongue or grooved rail by spiders a, which are similar to those used in ordinary switches.

F is the siding-rail, and it extends for some distance beyond the stub-joint in the main line. This rail is slightly higher at and for some distance upon each side of the stub-joint than the main-line rail. This elevation is 25 shown in Fig. 6, the drawing being distorted, in actual practice the siding-rail being only sufficiently elevated to raise the wheel clear of the main track to protect the stub—say one-quarter of an inch.

G is a guard-rail, similar in construction to the guard-rails used in nearly all switches, and whose purpose and operation is obvious.

In Figs. 3, 4, and 5 the plate or switch-chair A is represented as having projections

e and f, for holding the siding-rail F and the 50 main-line rail in place, and also with a projection, g, against which the stub-rail D bears when the switch is set for the siding. This plate may be either with or without these projections, and may be of any of the forms of 55 switch-chairs generally in use.

When the switch is set for the main line, as shown in Fig. 1, it will be seen that the car or cars will pass over without the least jar or scraping. When the switch is set for the siding, as shown in Fig. 2, the flanges of the wheels on the left of the car will be caught by the point of the grooved rail B, and the wheels on the right of the car, having been forced over by the guard-rail G, will bear upon both 60 the main-line rail and the siding-rail F, the slight elevation in the latter being near or equal to the difference in diameter between the outside and inside of the tread of the wheel. The elevation in this siding-rail is simply 65 for the purpose of protecting the stub-joint, and not to elevate the cars to pass them from one set of rails to another, as is the case in one or more well-known switches.

My switch is furnished with springs H H, 75 whose purpose is to allow a train which may be approaching the switch from the rear to force the switch over, and so pass through in safety. The arrangement of these springs is well known, and will need no further description.

Having thus described my invention, I claim—

1. The combination, in a switch, of the stub D, placed between the point and the siding-rail F, grooved rail B, guard-rail G, and siding-rail 85 F, all substantially as and for the purposes set forth.

2. The combination, in a switch, of the grooved rail B, stub D, elevated siding-rail 90 F, and guard-rail G, the whole arranged and operating substantially as and for the purposes set forth.

GEO. McCALL.
